C. E. FULLER

ANTIFRICTION BEARING

Filed Jan. 11, 1923

Fig. 2.

Inventor
C. E. Fuller
by James R. Hodder
attorney

UNITED STATES PATENT OFFICE.

CLAUDE E. FULLER, OF NEW YORK, N. Y.

ANTIFRICTION BEARING.

Application filed January 11, 1923. Serial No. 612,014.

To all whom it may concern:

Be it known that I, CLAUDE E. FULLER, a citizen of the United States, and a resident of New York, in the county and State of 5 New York, have invented an Improvement in Antifriction Bearings, of which the following description, in connection with the accompanying drawings, is a specification, like reference characters on the drawings 10 representing like parts.

My present invention relates to conveyors, and more particularly to an anti-friction roller for gravity conveyors.

In my prior Patent No. 1,487,326, dated 15 March 18, 1924, for an improved assembling table, I have described and claimed an assembling table for assembling a plurality of rows of bricks in position to be operated upon by a mechanical lifting device, the top 20 of such assembling table being comprised of a plurality of parallelly arranged grooves or guideways in the bottom of which grooves or guideways are located anti-friction rollers, such anti-friction rollers being 25 of a character to allow the bricks as they are guided onto the assembling table to slide along the length of the grooves or guideways by gravity. Such bricks are in practically a semi-dry condition; that is, they 30 have just issued from a mechanical drier where the excess of moisture has been driven off and the bricks tempered to a degree to allow safe handling and piling thereof into a kiln preparatory to firing the same. Such 35 bricks are, therefore, extremely friable and difficulty has been experienced with the type of anti-friction rollers heretofore employed because of the tendency of the anti-friction rollers to become clogged with dirt and dust 40 and the stopping of a single anti-friction roller in one of the series of such rollers located at the bottom of the grooves or troughs in the assembling table is sufficient to prevent the assembling table from functioning 45 in a suitable manner. Various forms of anti-friction rollers have been employed and suggested, none of which have been satisfactory, as all those heretofore employed have been of such a construction as 50 not to prevent the accumulation of dirt, dust, grit, and the like at a vital point.

In my present invention I have designed an improved anti-friction roller designed to obviate the objectionable features here-

tofore existing in prior apparatus and have 55 so designed my improved anti-friction roller that all dust entering or sifting downwardly past the roller is prevented from coming into engagement with the rolling part of such anti-friction roller, means being provided for guiding such dirt, dust, and grit away from the rotating member and also the anti-friction bearing therefor. 60

The object of my invention, therefore, is 65 an improved anti-friction roller for use in gravity conveyors and the like.

In the accompanying drawings illustrating preferred embodiments of my invention,

Fig. 1 is a vertical section through one 70 of the side members of a groove or guideway in an assembling table showing the method of assembling the anti-friction rollers in position thereon, two of such rollers being shown;

Fig. 2 is a side elevation of Fig. 1, and 75

Fig. 3 is a vertical section similar to Fig. 1, but showing a modified form, of my invention.

Referring to the drawings, 10 designates 80 an elongated strip or plate of metal forming one of the side walls of a longitudinal groove or guideway such, for example, as that shown and described in my patent co-pending application above referred to, and such strip or wall 10 is provided with a 85 plurality of spaced perforations 11 lying in a horizontal plane, but one of which perforations being shown.

My improved anti-friction roller comprises a central hub 12 of hardened steel 90 perforated to receive a threaded bolt 13 of a diameter suitable for passage through the perforation 11 in the strip or plate 10. This hub 12 is provided with a circumferential groove 14 intermediate its ends and in such groove 14 run a plurality of bearing balls 15 shown in dotted position in Fig. 2. 16 designates a cup shaped member of any suitable outside diameter, and the web or flange 95 of this member is forced upwardly, as shown at 17, into the cup, and the center of such web is cut away to provide a hole or perforation 18 slightly greater in diameter than the outside diameter of the hub 12. Two of these cup shaped members are utilized 100 in building a complete anti-friction roller, being placed end to end, as shown in Fig. 1, and the webs thereof secured to- 105

gether in any suitable manner, the portion 17 surrounding the bearing balls 15 and forming a ball race therefor.

The anti-friction roller resulting from the construction above described is that usually employed heretofore for purposes of this character and it has been found that dust, dirt, or grit coming from the material being transported on the rollers will sift through the opening 18 around the hub 12 and into the ball race formed by the portions 17 of the cup shaped members 16, clogging the ball race and preventing the bearing balls from functioning with the cup shaped members and the hub 12 in the usual manner.

To obviate this objection, I have provided discs 19 of substantially cone shape, provided with a central opening of the same diameter as the outside diameter of the hub 12, it being necessary, therefore, in assembling the disc 19 on the anti-friction bearing structure to use considerable force. One of the discs 19 is provided for each of the cup shaped members 16 and the use of such disc insures that any dust, dirt, or grit falling off the anti-friction rollers 16 will strike a disc 19 and be deflected away from the opening or perforation 18 in the portion 17 of the cup shaped members 16. In assembling my improved anti-friction roller in position on the elongated strip or plate 10 I utilize the threaded bolt 13 which passes through the opening 11 and place on the outer end of such threaded bolt 13 another anti-friction roller of the construction above described, holding both such anti-friction roller structures in position, one on each side of the strip or plate 10, by means of the nut 20. The hubs 12 are therefore stationary as are also the discs 19 while the cup shaped

members forming the anti-friction roller proper are allowed to freely rotate on the bearing balls 15.

In Fig. 3 I have illustrated a modification of my invention above described, such modification consisting of a disc 21 pressed on, and secured to, the hubs 12 in the manner above described with respect to the disc 19 but the outer periphery of such disc 21 is flared upwardly and outwardly, terminating in a point in alignment with the top of the cup shaped members 16 as designated by the numeral 22. An anti-friction roller constructed according to the modification illustrated in Fig. 3 operates in identically the same manner as the anti-friction roller illustrated in Fig. 1.

While I have necessarily shown and described the preferred embodiments of my invention somewhat in detail, it is to be understood that I may vary the arrangement and construction of parts comprising my device within wide limits without departing from the spirit of the invention.

Having thus described my invention, what I claim as new is:

An improved anti-friction roller comprising a stationary hub, cone shaped dust and dirt excluding discs mounted on said hub and converging inwardly at their peripheries to define a substantially circular cone shaped chamber, and a wheel having its body portion lying in the substantially circular cone shaped chamber and having its periphery lying in a cylinder and housing the periphery of the dust excluding cones.

In testimony whereof, I have signed my name to this specification.

CLAUD E. FULLER.
